(57) **CLAIM**

The ornamental design for a needle holder, as shown and described.

DESCRIPTION

FIG. 1 is a bottom perspective view of a needle holder in accordance with the new design;

FIG. 2 is a left side perspective view thereof;

FIG. 3 is a right perspective view thereof;

FIG. 4 is a top plan view thereof;

FIG. 5 is a bottom plan view thereof;

FIG. 6 is a front, top perspective view thereof; and,

FIG. 7 is a rear, top perspective view thereof.

FIGS. 1-5 shown as broken in the middle and embraced with a bracket to indicate that no particular length is claimed. The broken line showing portions of a needle holder is included for the purpose of illustrating environmental structure and forms no part of the claimed design.

1 Claim, 7 Drawing Sheets
